United States Patent Office

Des. 213,862
Patented Apr. 22, 1969

213,862

PAINT CAN LID

Thomas V. O'Leary, 1722 Martins Lane,
Gladwyne, Pa. 19035

Original design application Mar. 16, 1967, Ser. No. 6,252,
now Patent No. 212,185, dated Sept. 10, 1968. Divided
and this application Oct. 13, 1967, Ser. No. 9,450

Term of patent 14 years

Int. Cl. D9—99

U.S. Cl. D9—264

Fig. 1

Fig. 2

Fig. 3

Fig. 4

FIGURE 1 is a plan view of a paint can lid embodying my new design;

FIGURE 2 is a side elevation of the paint can lid shown in FIGURE 1;

FIGURE 3 is an end view of the paint can shown in FIGURES 1 and 2; and

FIGURE 4 is a view taken along the line IV—IV of FIGURE 2.

This is a division of my earlier application Serial No. D. 6,252 of Mar. 16, 1967, now design Patent No. 212,185 of Sept. 10, 1968.

I claim:

The ornamental design for a paint can lid, as shown and described.
